UNITED STATES PATENT OFFICE.

GUSTAV L. JAEGER, OF NEW YORK, N. Y., AND ADOLF FABER DU FAUR,
OF NEWARK, NEW JERSEY, ASSIGNORS TO SAID JAEGER.

MANUFACTURE OF CELL-CASES.

SPECIFICATION forming part of Letters Patent No. 296,288, dated April 1, 1884.

Application filed June 26, 1883. (No model.)

To all whom it may concern:

Be it known that we, GUSTAV L. JAEGER, a citizen of the United States, residing at New York, in the county and State of New York, and ADOLF FABER DU FAUR, a citizen of the United States, residing at Newark, in the county of Essex and State of New Jersey, have invented new and useful Improvements in the Manufacture of Cell-Cases, of which the following is a specification.

Our invention relates to the manufacture of cell-cases—also known as “frames” or “trays”—from straw-board or other similar material, to be used for packing eggs in boxes during transportation, and for other similar purposes, such cases being composed of two intersecting series of strips or partitions, which, for convenience, are called “longitudinal strips” and “cross-strips,” respectively, 20 and which are interlocked by means of partial cross cuts or slots.

One of the objects of our invention is to present a series of continuous longitudinal strips, for interlocking therewith successive cross-strips with an intermittent motion, the longitudinal strips being stationary while the operation of interlocking is performed. Another object is to vary the extent of such intermittent motion of the longitudinal strips 30 without varying the time intervals thereof, and thereby shorten the space between two successive cross-strips where the longitudinal strips are cut to form the cases. These and other objects we have accomplished by the 35 novel method and means hereinafter described, and illustrated in the accompanying drawings, in which—

Figure 1 represents a longitudinal section. Fig. 2 is a side elevation. Fig. 3 is a horizontal section on the line $x-x$, Fig. 1. Fig. 4 is a detail cross-section on the line $y-y$, Fig. 1. Fig. 5 shows the form of the longitudinal strips when cut off to form a case. Fig. 6 shows a modification of the longitudinal strip cutting and slotting mechanism.

Similar letters indicate corresponding parts.

The letter A designates a frame supporting in a proper manner the parts of the machine used in carrying out our invention. In this 50 frame is arranged a bed or table, C, which acts

as a support for the longitudinal strips 6 in presenting the same to the cross-strips 7, as well as before and after that period. The longitudinal strips are taken from a web, B, having a suitable width to produce the desired 55 number of such strips, while the cross-strips are cut from a web, D, having a suitable width to produce strips of the desired length. Rotary cutters E E, arranged above and below the bed C, to coact with each other, serve to 60 produce the longitudinal strips from the web B, whence such strips pass between feed-rollers F F, thence under a reciprocating die, G, and through guides H, when they are presented to the cross-strips. The feed-rollers F F 65 receive an intermittent motion at regular intervals to properly advance or present the longitudinal strips, and it will be noticed that the cross-strips may thus engage the longitudinal strips with accuracy, not only as to position, but also as to effect or execution, inasmuch as the longitudinal strips are entirely stationary during such engagement of the cross-strips. The die G is shaped to crosscut or slot the longitudinal strips, as at 8, Fig. 5, 70 in the proper manner to receive the cross-strips, while the guides H are arranged to turn or deflect the longitudinal strips severally from a flat to an upright position, as shown. The web D passes between feed-rollers I I, and 75 thence under a reciprocating die, J, when it is united or interlocked with the longitudinal strips. The feed-rollers I I, like the rollers F F of the longitudinal strips, receive an intermittent motion at regular intervals, to properly advance the web D, and the die J is constructed with knives, which, together with a suitable counter-die, operate to simultaneously crosscut or slot such web and sever it to produce a cross-strip substantially of the form 80 shown in Fig. 5—that is to say, the leading end of the web is first cut or slotted in the proper manner. The web is then advanced a sufficient distance to cause such end to interlock with or partially enter into the longitudinal strips, when the web is cut transversely at the proper point to produce a cross-strip of the required height, while it is also cut or slotted inward from the line of the cut for the next strip. 85

The feeding of the web D to its place before severing it, as just described, is important, because it insures the proper reception of the strip by the part intended to receive it, and this 5 feature can be used to advantage in other machines.

The extent of the intermittent motion of the longitudinal-strip feed-rollers F F is varied by a reduction therein after a sufficient number of 10 cross-strips have been interlocked with the longitudinal strips to form a cell-case—say after every seventh cross-strip—the time intervals of motion of such rollers being, however, left regular to preserve the proper relation to 15 the cross-strip feed-rollers I I, and previous to each variation in such motion of the longitudinal-strip feed-rollers F F, and between the periods thereof, the longitudinal strips are cut or severed to form a cell-case by reciprocating 20 knives O, which are arranged at a point intermediate of the cross-strip-interlocking mechanism and the guides H. By this method of severing the longitudinal strips, the projecting ends 9, Fig. 5, of the cell-cases are 25 rendered short in comparison with the length of space between the cross-strips, and hence the loss of material is avoided, while by the position of the knives O they allow the proper movement of the longitudinal strips.

30 The distance between the die G and the point where the cross-strips are interlocked with the longitudinal strips is equal to or a multiple of the length of one cell-case—namely, a multiple of $a b$, Fig. 5—the variation in the 35 intermittent feed motion imparted to the longitudinal strip being so timed or regulated that the crosscuts or slots produced in such strips after one variation of motion shall be presented to the cross-strips after a succeeding 40 variation thereof, and hence the proper adjustment of the longitudinal strips to the cross-strip is insured relatively to the short ends of the cell-cases. To allow of compensating for any 45 inaccuracy in feeding the longitudinal strips, the distance between the die G and the strip-interlocking point is made adjustable within certain limits by arranging such die to move in ways G', which are adjustably secured to the machine-frame. The relative operation of the 50 parts described is as follows: Assuming that the leading end of the web D has been properly crosscut or slotted, the cross-strip feed-rollers I I act on the web to advance it the required distance to interlock the leading end 55 of the web with the longitudinal strips. The cross-strip-forming die J then acts on the web named, while the longitudinal-strip-forming die G acts on the web B, the longitudinal-strip cutters E E and feed-rollers F F in the mean- 60 time remaining stationary. Then, when both dies J G and the cross-strip feed-rollers I I have ceased to act, the longitudinal-strip cutters and feed-rollers are brought into operation to cut and advance the proper web, and 65 so on.

At a point in rear of the cross-strip-inter-

locking mechanism is arranged a reciprocating lever-frame, L, comprising a blade, N, which strikes against the top edge of successive cross-strips between the periods at which 70 the longitudinal strips are presented, thereby “bottoming” or driving home the cross-strips.

The bed C is by preference inclined downwardly in the direction of the motion of the 75 longitudinal strips, and by this means a tendency is given to such strips to advance by gravity.

For the purpose of producing the described motions of the parts, the following means are 80 used, it being, however, understood that the same may be modified in known ways: A driving-shaft, P, is provided with a crank, P', Fig. 2, to which is connected one arm of an elbow-lever, P², the other arm of which carries a push-pawl, P³, engaging a toothed wheel, P⁴, which is geared with the shaft of one of the longitudinal-strip feed-rollers F F, these 85 rollers being geared together and with the rotary cutters E E. One tooth of the wheel 90 P⁴ is shortened, the remainder being of equal length, and hence such wheel is moved a reduced distance by the action of the pawl P³ once in each revolution thereof, with a corresponding effect on the feed-rollers. With the 95 driving-shaft P is geared a counter-shaft, Q, Figs. 1 and 4, which carries two cams, Q' Q², one acting on the longitudinal-strip cutting or slotting die G, and the other acting on the stock 100 O' of the knives O, a spring, O², counteracting the cam last named, which is brought into play at the proper periods by a lever, Q³, engaging a cam, Q⁴, which also is geared with the driving-shaft P. With the driving-shaft P is also 105 geared a cam, R, which engages a lever, R', carrying a push-pawl, R², for actuating a toothed wheel, R³, mounted on the shaft of one of the cross-strip feed-rollers I I, such cam and a fellow cam mounted on the same shaft, R⁴, also acting on a spring-retracted slide-rod, 110 R⁵, connected to the cross-strip-forming die J. On the cam-shaft R⁴ are mounted additional 115 cams, S, which serve to lift the bottoming-frame L off from the cross-strips, such frame descending by gravity.

If desired, the longitudinal-strip cutting or slotting die G may be omitted, and a rotary cutter, U, Fig. 6, be used to slot as well as to cut the strips from the web B; but in this case the strips should be alternately conducted over 120 and under a roller, U', for separating them from each other. Previously-prepared longitudinal strips as well as cross-strips may also be intermittently fed by feed-rollers or other mechanism; and, if desirable, the flat or horizontal portions of the guides H may be arranged at different levels, one overlapping the other, to allow the guides to be made of increased width, in distinction from being arranged in the same plane, as in this example.

What we claim as new, and desire to secure by Letters Patent, is—

1. In the manufacture of cell-cases from continuous longitudinal strips and from cross-strips, the step herein described, consisting in presenting such continuous longitudinal strips with an intermittent motion and interlocking therewith the cross-strips while said longitudinal strips are stationary.
2. In the manufacture of cell-cases from continuous longitudinal strips and from cross-strips, the step herein described, consisting in presenting such longitudinal strips with an intermittent motion, and between the periods of such motion, and while said longitudinal strips are stationary, both interlocking there-with the cross-strips and forming therein crosscuts or slots to receive the cross-strips.
3. The within-described method of making cell-cases, which consists in presenting a series of longitudinal strips with an intermittent motion varying in extent, interlocking therewith successive cross-strips, and severing the longitudinal strips between the periods of such motion previous to each variation therein.
4. In the manufacture of cell-cases, the step herein described, consisting in feeding to and partially interlocking in its place the leading end of a continuous web before cutting it.
5. The within-described method of making cell-cases, which consists in presenting a series of continuous longitudinal strips interlocking therewith the leading end of a continuous web, severing the latter at the proper point to form a cross-strip, bottoming the cross-strip, and severing the longitudinal strips into the proper length for a case.
6. In a machine for making cell-cases from a series of continuous longitudinal strips and cross-strips, a mechanism, substantially as described, for presenting the longitudinal strips with an intermittent motion of varying extent at regular intervals, in combination with a mechanism, substantially as described, for interlocking the cross-strips with the longitudinal strips at similar intervals, substantially as and for the purpose described.
7. In a machine for making cell-cases from a series of continuous longitudinal strips and cross-strips, the combination of intermittently-operating mechanism for forming and pre-

senting the longitudinal strips, and similar mechanism for forming and interlocking the cross-strips while said longitudinal strips are stationary, substantially as and for the purpose described.

8. In a machine for making cell-cases from a series of continuous longitudinal strips and cross-strips, the combination of intermittently-operating mechanism, substantially as described, for presenting the longitudinal strips, similar mechanism for interlocking the cross-strips with the longitudinal strips, guides for turning the longitudinal strips from a flat to an upright position, and reciprocating cutters, arranged at a point intermediate of the strip-interlocking mechanism and the guides, to act on the longitudinal strips, substantially as and for the purpose described.

9. In a machine for making cell-cases from a series of continuous longitudinal strips and cross-strips, the combination of rotary cutters for producing the longitudinal strips, intermittently-operating feed-rollers for advancing the longitudinal strips, guides for turning the longitudinal strips from a flat to an upright position, and a reciprocating die, arranged at a point intermediate of the feed-rollers and guides, to act on the longitudinal strips, substantially as and for the purpose described.

10. In a machine for making cell-cases from a series of continuous longitudinal strips and cross-strips, the combination of intermittently-operating mechanism, substantially as described, for presenting the longitudinal strips, similar mechanism for interlocking the cross-strips with the longitudinal strips, and a bottoming mechanism, substantially as described, arranged at a point in rear of such interlocking mechanism, to act on the cross-strips between the periods at which the strip-presenting mechanism operates, substantially as and for the purpose described.

In testimony whereof we have hereunto set our hands and seals in the presence of two subscribing witnesses.
